Alfred P. Daniel INVENTOR.

BY

Hardway & Cather ATTORNEYS.

UNITED STATES PATENT OFFICE.

ALFRED P. DANIEL, OF HOUSTON, TEXAS.

DESIGN FOR A BADGE, BUTTON, OR PIN.

59,623.

Specification for Design.

Patented Nov. 15, 1921.

Application filed June 20, 1921. Serial No. 479,139. Term of patent 3½ years.

To all whom it may concern:

Be it known that I, ALFRED P. DANIEL, a citizen of the United States, residing at Houston, in the county of Harris, State of Texas, have invented a new, original, and ornamental Design for a Badge, Button, or Pin, of which the following is a specification, reference being had to the accompanying drawing, forming part thereof.

The figure is a plan view of a badge, button, or pin showing my new design.

I claim:

The ornamental design for a badge, button, or pin as shown.

ALFRED P. DANIEL.

Witnesses:

W. H. DUNLAY,
E. V. HARDWAY.
